(57) CLAIM

The ornamental design for an accessory holder, as shown and described.

DESCRIPTION

FIG. 1 is an isometric view of an accessory holder showing our new design;

FIG. 2 is a front elevational view thereof;

FIG. 3 is a right side elevational view thereof, in which the left side elevational view would be a mirror image;

FIG. 4 is a top elevational view thereof;

FIG. 5 is a bottom elevational view thereof; and,

FIG. 6 is a rear elevational view thereof.
